United States Patent Office

Des. 198,782
Patented Aug. 4, 1964

198,782

BARBER CHAIR

Fred J. Piotraschke, 2 N. Tealbrook Drive,
Creve Coeur, Mo.

Filed Sept. 30, 1963, Ser. No. 76,798

Term of patent 14 years

(Cl. D15—3)

FIG. 1

FIG. 2

I claim:

The ornamental design for a barber chair, substantially as shown.
